CLAIM

The ornamental design for a cabinet drawer, as shown and described.

DESCRIPTION

FIG. 1 is a top perspective view of a cabinet drawer showing a first embodiment of my new design;

FIG. 2 is a front elevational view thereof;

FIG. 3 is a left elevational side view thereof;

FIG. 4 is a right elevational side view thereof;

FIG. 5 is a top plan view thereof;

FIG. 6 is a bottom plan view thereof;

FIG. 7 is a top perspective view of a second embodiment of a cabinet drawer showing my new design;

FIG. 8 is a front elevational view thereof;

FIG. 9 is a rear elevational view thereof;

FIG. 10 is a left elevational side view thereof;

FIG. 11 is a right elevational side thereof;

FIG. 12 is a top plan view thereof;

FIG. 13 is a bottom plan view thereof; and,

FIG. 14 is an enlarged perspective view of a portion of the cabinet drawer shown in FIG. 7.

The portions shown in broken lines form no part of the design.
